UNITED STATES PATENT OFFICE.

CATHERINE E. SCOTT, OF MILWAUKEE, WISCONSIN.

PAPER-CRIMPING MACHINE.

Application filed July 9, 1926. Serial No. 121,407.

This invention relates to improvements in paper crimping machines.

It is one of the objects of the present invention to provide a machine for ruffling or crimping crepe paper for decorative purposes.

A further object of the invention is to provide a paper crimping machine attachable to a support and easily manually operable to quickly and efficiently crimp or ruffle paper.

A further object of the invention is to provide a paper ruffling machine having an adjustment to accommodate the machine to material of different thicknesses, also controlling in a measure, the character of the crimp imparted to the paper.

A further object of the invention is to provide a paper crimping or ruffling machine which is very simple in construction and operation, is inexpensive to manufacture, is strong and durable, and is well adapted for the purposes described.

With the above and other objects in view the invention resides in the improved paper crimping machine and its parts and combinations as set forth in the claims and all equivalents thereof.

In the accompanying drawing in which the same reference characters indicate the same parts in all of the views:

Fig. 1 is a side view of the paper crimping machine;

Fig. 2 is a plan view thereof; and
Fig. 3 is an end view thereof.

Referring now more particularly to the drawing it will appear that the numeral 5 indicates a bracket portion having at its ends upstanding bearing portions 6 and 7 in which a shaft 8 is journaled. Depending from the bracket portion is a clamping jaw 9 fitted with a turn screw 10 by which means the device may be clamped to a table or support 11.

The outer end portion of the shaft 8 has fixed thereto a crank 12 for manually rotating the shaft. The medial portion of the shaft, between the bearing portions 6 and 7, has fixed thereto, by means of a pin 13, a ribbed cylinder 14.

Extending upwardly and angularly from one end of the bracket portion is an arm 15, enlarged at its upper end portion as at 16, the portion 16 being provided with a bore to receive a shaft 17. A bearing member 18 having bifurcated end portions 19

adjacent the portion 16, receives the end portions of the shaft 17 whereby the bearing member 18 is pivotal with respect to the arm 15.

An upper shaft 20 extends laterally from the bearing member 18 and revolvably mounted thereon is an upper ribbed cylinder 21 similar to the cylinder 14.

A lug portion 22 extends upwardly from the portion 7 for engagement with a depending lug portion 23 formed on the bearing member 18, both of said portions having internally threaded bores to receive the shank of an adjusting screw 24. A spring 25 is coiled about the shank of the screw and is confined between the head of the screw and the upper surface of the lug portion 23. This arrangement permits slight yielding pivotal movement of the member 18 and upper cylinder 21 and also by threading or unthreading the screw the distance between the two cylinders may be adjusted.

In operation, crepe paper or other material to be ruffled or crimped is placed between the two cylinders and the handle of the crank is turned to rotate the cylinder 14 and thereby advance the material. The action of the ribs of the cylinders on the material causes it to become ruffled or crimped as indicated at 26 in Fig. 3. Also, as explained, by means of the pivotal mounting of the upper cylinder bearing member 18 and the adjusting screw 24 the distance between the two cylinders may be adjusted to accommodate the machine to material of different thicknesses. The same adjustment may also serve to regulate in a degree the depth or character of the crimp to be imparted to the material.

From the foregoing description it will be seen that the improved paper crimping machine is of very simple and novel construction, and is well adapted for the purpose set forth.

What I claim as my invention is:

1. A crimping machine, comprising a bracket, a shaft journaled therein, a ribbed cylinder carried by said shaft, means for revolving the shaft, an arm extending angularly upwardly from the bracket, a bearing member formed with a bifurcated end portion, the upper end portion of said arm being engaged between said bifurcated end portion, a pin pivotally connecting the bearing member to said arm, a second shaft carried by said bearing member and parallel to

said first shaft, a cooperating ribbed cylinder carried by said second shaft, and an adjustable, yielding connection between the bearing member and the bracket.

- 5 2. A crimping machine, comprising a bracket formed with an off-set lug portion, a shaft journaled in said bracket, a ribbed cylinder carried by the shaft, means for revolving the shaft, an arm extending angularly
10 upwardly from the bracket, a bearing member formed with a bifurcated end portion, the upper end portion of said arm being engaged between said bifurcated end portion, a pin pivotally connecting the bearing mem-

ber to said arm, said bearing member being 15 formed with an off-set lug portion adjacent the bracket off-set lug portion, a second shaft carried by said bearing member and parallel to said first shaft, a cooperating ribbed cylinder carried by said second shaft, 20 a set screw threaded through said bearing member, lug portion and into the bracket lug portion, and a spring coiled about said screw between its head and the upper surface of the bearing member lug portion. 25

In testimony whereof, I affix my signature.

CATHERINE E. SCOTT.
